FIG.3.

FIG.1.

UNITED STATES PATENT OFFICE

2,190,437

WATER CLOSET

James M. Teahen, Detroit, Mich.

Application October 18, 1937, Serial No. 169,745

3 Claims. (Cl. 4—14)

The invention relates to water closets of that type in which the tank is separate from the bowl but directly supported thereon. With such constructions the water discharged from the tank 5 passes directly into the bowl but a separate inlet conduit is required. Also, it is necessary to provide suitable means for firmly attaching the tank to the bowl. With my improved construction I employ the inlet conduit as a tie connection for 10 securing the tank to the bowl and I also preferably combine this with the fitting which forms the seat for the outlet valve. The invention, therefore, consists in the above novel features of construction, together with certain additional 15 features as more fully hereinafter set forth.

In the drawing:

Figure 1 is a vertical longitudinal section through the water closet;

Figure 2 is a plan view thereof;

Figure 3 is a cross section on line 3—3 of Figure 1.

A is the bowl which may be of any suitable construction excepting as hereinafter described. B is a hollow shelf integral with the bowl and 25 projecting rearward therefrom. C is a hollow rim at the top of the bowl which is connected with the space within the hollow shelf and is provided on its underside with a series of jet apertures D. E are partitions within the rim 30 C forming therebetween a chamber F located at a point diametrically opposite the hollow shelf B. The partitions E are provided with comparatively shallow but wide ports E' extending through the top portions thereof forming communication between the chamber F and other portions of the rim. There is also an elongated discharge port F' communicating with the chamber F through the bottom thereof. The construction just 35 described is one in which air within the hollow rim may be displaced by incoming water from the hollow shelf with the avoidance of noise.

G is the tank which rests upon the shelf B and extends on opposite sides thereof. The bottom G' of this tank has a port G² therein which 40 registers with an opening in the top of the hollow shelf and forms a passage. This permits the flow of water from the tank through the hollow shelf into the rim C from which it is discharged through the ports D, the air having first been 45 displaced through the ports E' and F'. The tank G is further provided in one wall thereof with an overflow passage G³, the top of which is slightly above the normal level of the water in the tank, while the bottom registers with a port B' 50 in the hollow shelf.

To securely attach the tank to the bowl and at the same time to form a water inlet connection to the tank I employ a fitting H. The upper end of this fitting has an annular portion H' which surrounds the port G² and forms a seat for the outlet or flush valve, not shown. Centrally within this annular portion and connected thereto by hollow spokes H² is a spud H³ which passes downward through the port G² and through an aperture in the lower wall of the hollow shelf B. 10 The lower end of this spud is threaded to receive a clamping nut I for drawing the fitting down upon the tank and clamping the latter to the shelf. A sealing gasket J is placed between the nut I and the bottom of the shelf and an annular gasket K is inserted between the seat portion H' and a conical wall of the aperture G². Below the nut I there is a sufficient extension of the threaded portion for securing to the spud the water inlet conduit. A gasket K' between the tank and the shelf seals about the ports G² and B'.

The specific construction of the water inlet and outlet valve which cooperate with the fitting just described forms the subject matter of another application for patent Serial No. 104,557, filed October 7, 1936, and I will, therefore, omit description of such parts. It will be sufficient to state that an inlet valve L of the flexible diaphragm type is arranged within the portion H³ 30 and the water passing said valve when open, flows through the hollow spokes H² into the tank. Also, the water is normally retained in the tank by a flush valve M seated on the member H'. My invention is not, however, confined to this 35 specific construction, but may be used with any type of water inlet which also constitutes a tie connection for securing the tank to the bowl.

The tank G is preferably formed with a top portion G⁶ which is integral with the side walls 40 and which covers a large portion of the interior of the tank. There is, however, a central opening G⁴ which is of sufficient size to admit the fittings and which is normally closed by a cover G⁵. It is the usual practice to form tank covers of 45 dimensions slightly in excess of the length and width of the tank, so as to overlap the side and end walls thereof. On account of the thickness of the cover required to impart to the same the necessary strength, it adds a considerable 50 amount to the weight of the tank. With my improved construction the integral part of the top may be formed relatively thin as it is reinforced by its union with the side and end walls. Also, the detachable cover is sufficiently small in area 55

not to require a great thickness. Consequently, the total weight of the tank and cover is considerably less than with constructions of tanks having the same capacity, as heretofore made.

- 5 This is particularly advantageous where the tanks are made of vitreous material.

What I claim as my invention is:

1. In a water closet, the combination of a bowl having a hollow shelf extending rearward therefrom, a tank supported on said shelf provided with an outlet port through the bottom thereof registering with a corresponding port in said hollow shelf, and a combined inlet and outlet fitting having a seat portion for a water discharge valve 10 surrounding the port in the bottom of the tank and a central water inlet conduit passing through said port and the bottom of said shelf and forming a tie connection between the tank and bowl.
- 15 2. In a water closet, the combination of a bowl

having a rearward extension, a tank resting on said extension, and a water supply conduit for said tank passing centrally through said extension and the bottom of the tank forming the sole tie connection therebetween.

3. In a water closet, the combination of a tank having an outlet port through the bottom thereof and an overflow passage formed in a side wall, a bowl having a rearwardly extending hollow shelf on which said tank rests and provided with openings which register respectively with said outlet port and overflow passage, an annular sealing gasket surrounding all of said openings, and a water inlet fitting passing through said hollow shelf and bottom of the tank within said annular gasket and forming a means for securing said tank on said shelf.

JAMES M. TEAHEN.
